HEAT EXCHANGER

Julius Benzinger, Queens Village, N. Y., assignor
to The Griscom-Russell Company, New York,
N. Y., a corporation of Delaware

Application April 11, 1934, Serial No. 720,017

16 Claims. (Cl. 257—32)

This invention relates to a combined condenser and sub-cooler. The apparatus is adapted to do all work in which it is desired to condense vapor and cool the condensate, but it is particularly for use in connection with oil refining.

In the operation of a condenser, it is desirable that the condensate at any point shall not be at a higher temperature than the vapors in contact therewith. Generally, that condition will be substantially maintained as long as the vapor and condensate remain closely associated in numerous paths and in a heat-exchanging relation. But if, as in the usual type of multi-pass construction, the vapor and condensate are allowed to separate at the end of each pass, there is a tendency for the condensate, being of concentrated volume, to thereafter flow along in contact with only a small part of the cooling surfaces of the condenser. As a result, the condensate temperature at the end of a given pass of the apparatus tends to be higher than the vapor temperature at the same point. It is an object of the present invention to provide a condenser in which the flowing condensate is exposed to an increased area of cooling surface, so as to maintain its temperature substantially as low as, or lower than, that of the vapor in contact therewith.

A further problem frequently encountered in the operation of condensers of the ordinary type, is the inefficient utilization of cooling surfaces in certain parts of the apparatus. In certain applications peculiar conditions of temperature, pressure, volume, or degree of saturation of the vapor may require particular combinations of cooling area and vapor velocities for efficient functioning. For example, it is not unusual for most of the condensation to take place in the first passes of the condenser, so that only lean, dead gases flow through the final passes of the apparatus; at the same time, with the usual forms of construction, the condensate at the outlet of the condenser is only slightly sub-cooled. It is an object of the present invention to provide a combination condenser and sub-cooler in which all cooling surfaces will be utilized to the best advantage; whereby the efficiency of the apparatus may be improved, and the condensate substantially sub-cooled.

A further object is to provide such apparatus in which the means for proportioning the condensing and sub-cooling areas may readily be changed to meet a change in conditions of operation.

Another object is to provide in connection with

such apparatus means to facilitate the drainage of condensate from the apparatus in case of shutdown.

In general, the objects of my invention may be obtained by condensing apparatus having a pair of headers, a plurality of tubes interconnecting said headers, means for supplying condensable vapor to the apparatus, and means for bringing the flowing condensate into contact with a large area of cooling surface. The latter means may take a variety of forms. It may be a dam-like element by which a large part of the cooling surface may be flooded with condensate. In a multi-pass condenser of the atmospheric type, such dam elements are most conveniently associated with the headers, and are designed to divide the flow of condensate among a large number of the lower tubes in at least one pass. It is generally desirable to provide drainage means in connection with such dam elements.

An alternative form of means for controlling the amount of cooling surface effective upon the condensate, is the subdivision of the flow of condensate from any pass into a plurality of isolated, vertically-spaced paths of flow in the following pass.

The various objects of my invention will be more apparent upon considering the following detailed description of certain embodiments thereof. This description is to be taken in conjunction with the accompanying drawings, in which:

Fig. 1 is a vertical section view of a condenser embodying my invention;

Fig. 2 is a horizontal section view taken along the plane 2—2 of Fig. 1 showing details of construction;

Fig. 3 is a vertical section view taken along the plane 3—3 of Fig. 6, and showing another embodiment of my invention;

Fig. 4 is a vertical section view of the lower part of a header of Fig. 3, taken along the plane 4—4 of Fig. 6, and showing details of construction;

Fig. 5 is a transverse view of the inside face of the part of the cover plate shown in Fig. 4;

Fig. 6 is a horizontal section view taken along the plane 6—6 of Fig. 4, showing details of construction; and

Fig. 7 is a vertical section view showing another embodiment of my invention.

Similar numerals refer to similar parts throughout the several figures of the drawings.

One embodiment of my invention, illustrated in Fig. 1 of the accompanying drawings, comprises a plurality of tubes 10, the ends of said tubes being suitably mounted in the tube sheet castings 11 and 55

12. Casting 11 is shown with both an inlet connection 21 and an outlet connection 22. Both castings 11 and 12 have section separators 23 for providing multi-pass flow through the tubes.

5 Detachably secured to the casting 11 by any suitable means, such as the studs 25, are the dam plate 15 and the cover plate 13, this assembly constituting a header. In the same manner the dam plate 16 and cover plate 14 are secured to 10 the casting 12, forming the other header. The cover plates are provided with section separators 26 corresponding to separators 23 on the tube sheet castings, alternate separators 26 being provided with suitable openings 24 to allow flow between passes. The cover plates may also be provided with suitable means for lifting the condenser, such as eyelets 26.

20 Dam plates 15 and 16 are disposed between the cover plates and the tube sheet castings. In this embodiment, they are metallic sheets having apertures designed to allow the free flow of vapor and condensate at the inlet of a pass, but to prevent the discharge of condensate from one pass into the next except by flow over the dam. In Fig. 1, 25 the dam plates are shown clamped between the cover plates and the tube sheet castings by means of the studs 25. An alternative construction is to cast the dam elements integral with the cover plates.

30 Drainage plugs 17 pass through threaded holes in the cover plate and engage the drain ports 17' at the base of each dam element. Additional plugs may also be provided at various levels on each dam element for purposes pointed out below.

35 The operation of the embodiment illustrated by Fig. 1 is as follows:

The path of flow is indicated by arrows on the figure. When operation of the unit is begun, vapor, either alone or with some liquid, enters 40 the condenser through the inlet connection 21. The vapor passes through the upper tubes of the first pass and is cooled by the transmission of heat through the tubes to the external cooling medium. Condensate forming in the first pass drops into the space 27 at the end of the pass. 45 The liquid entering the inlet 21 falls to the bottom of the inlet space, flows through the lower-most tubes of the pass where it is somewhat cooled in the same manner as the vapor; whence 50 it passes into the space 27 behind the dam element. Since there is no liquid outlet from the pass except by flow over the dam edge 29, the liquid and condensate accumulate to that level, flooding all the tubes of the first pass below that level. After the level of the liquid reaches the 55 dam edge 29, it is apparent that the liquid entering through the inlet 21 will flow through the flooded tubes and over the dam at the same total rate that it enters the apparatus. The dam element is thus seen to effect an increase in the amount of cooling surface in contact with the liquid, and to cause a slower rate of flow through each tube flooded. The combined effect of these 60 features is to sub-cool the liquid the desired amount. It is apparent that the total flow over the dam is made up of whatever liquid may enter the inlet, increased by the amount of condensate forming in the upper tubes of the pass and dropping into the space 27. This entire overflow, together with uncondensed vapor from the upper 65 tubes, passes through the opening 24 to the next pass, where the same process is repeated. So also in each pass, until the lean vapor and cooled condensate pass through the outlet connection 22.

70 75 The level of the overflow openings in the dam

plates depends on the application for which the apparatus is to be used and is determined by many factors. For certain applications, it may be necessary to provide different proportions of cooling area for vapor and condensate than for other applications. The efficient usefulness of a given apparatus may, therefore, be greatly extended by providing several sets of dam plates which differ in the number of dam elements utilized, or in the level of the dam edges. Or, if desired, wide flexibility can be had by providing a plurality of drainage ports similar to 17', but arranged at different levels in each dam element; the effective overflow level of each dam element could then be varied by opening or closing these ports by means of the plugs 17 from the outside of the apparatus, and without interrupting operation. If no sub-cooling is desired, all drainage ports may be opened or both dam plates may be entirely removed, and the apparatus operated as a standard condenser.

20 When the condenser is shut down for any considerable length of time, or when the cover plate is to be detached for any purpose, it is desirable that any liquid held behind the dam elements should be drained off. To do this, it is only necessary to unscrew the plugs 17 until the cotter pins or similar devices 18 strike the cover plate, indicating to the operator that the drainage ports 17' are fully open.

30 The apparatus shown in Fig. 1 has a dam element in the first pass. Such a design is particularly adapted to an application where considerable liquid is admitted through the inlet connection 35. It is apparent that in such an application the same theoretical considerations apply to the liquid admitted through the inlet to the first pass as apply to the condensate entering subsequent passes through the openings 24. Consequently, 40 for the sake of clarity, the term "condensate", as used hereafter in this specification and the claims, will be understood to include such liquid admitted through the inlet.

45 Where only vapor enters the first pass, there would ordinarily be little necessity for immediately sub-cooling the condensate in the first pass; hence, the dam elements in the first pass or passes may be omitted. Such a construction is shown in Fig. 3, which also shows one way in which the dam elements may be constructed in- 50 integral with the cover plate.

55 Though the elements of the embodiment shown in Fig. 3 are fundamentally the same as those of the embodiment previously described, some of the structural details are quite different. The principal differences are in the construction of the cover plates 33 and 34 of Fig. 3. The integral construction of the cover plate and dam elements is effectively accomplished in a unique manner further illustrated by Figs. 4, 5 and 6. 60 The built-in dam elements 35 correspond functionally to the apertures in the dam plates 15 and 16 of Fig. 1, and operate in a similar manner. Thus, condensate collects in the space 27 behind the dam elements 35, and floods the tubes which 65 communicate with that space. The path of flow, indicated by arrows on the figures, is through the openings 36 at the sides of the cover plate, over the dam elements 35, down the center channel 37 to the inlet opening 38 of the next pass. 70 Flexibility in this embodiment may be obtained by providing several sets of cover plates having different overflow levels, or by using other means to raise or lower the effective level of the dam elements 35. Though for simplicity no drainage 75

means are shown in connection with Fig. 3, it is apparent that means similar to those which have been previously described are here applicable.

5 Figure 7 illustrates a means by which is effected the contact of the condensate with an increased cooling area without the use of dam elements. In this embodiment, there are provided in the headers auxiliary return bonnets which 10 divide the flow of condensate into isolated parallel paths as indicated by the arrows on the figure. These auxiliary return bonnets may be formed by providing additional separators 23' on the tube sheet casting cooperating with the inner cover plates 40. These inner cover plates are so situated within the header that they do not impede the flow of condensate and vapor from the tubes not included within the auxiliary return bonnet. The inner cover plates may be constructed 15 integral with the main cover plates 13 and 14 or they may be made detachable and held in position by any suitable means, as by attachment to either the tube sheet casting or the cover plate, or by being fitted between them.

20 25 By means of the auxiliary return bonnets of Fig. 7, it is seen that the condensate from all the tubes of a pass is prevented from separating from the vapor and collecting into a single body at the beginning of a pass. Thus, instead of flowing only through the lowermost tubes of the pass, the condensate is divided between the lowermost tubes of each isolated path. In this way the number of tubes through which condensate will flow is increased and the transfer of heat from the condensate to the cooling medium is greatly facilitated.

30 Though the embodiment of Fig. 7 shows both the vapor and the condensate confined to the same isolated paths, it is apparent that there will usually be no objection to allowing all the vapors to mix together at the beginning of each pass. Also, it is not essential that the separate paths of condensate flow shall be continuous through several passes; for it is generally immaterial in what 35 way the condensate is collected at the end of a pass, so long as it is divided into a plurality of vertically spaced paths upon entering the following pass.

40 It is to be understood that my invention is not limited to the exact forms of construction herein disclosed, for various modifications thereof are possible without departing from the spirit of my invention. For instance, the number of passes, their arrangement, and proportions are variable 45 within wide limits. Also, my invention may be applied to condensers of the enclosed type as well as to those of the atmospheric type illustrated.

I claim:

- 50 1. Apparatus of the type described, comprising a pair of headers, a plurality of tubes interconnecting said headers and providing cooling surface, means for supplying condensable vapor to said tubes, and means for controlling the flow 55 of condensate through said tubes to subject the same to varying areas of cooling surface as it progresses, to maintain the temperature of the condensate substantially as low as that of the vapor in contact therewith.
- 60 2. Apparatus of the type described, comprising a pair of headers, a plurality of tubes interconnecting said headers and providing cooling surface, means for supplying condensable vapor to said tubes, and means for directing the flow 65 of condensate into contact with a progressively

increasing area of cooling surface to maintain the temperature of the condensate substantially as low as that of the vapor in contact therewith.

3. Apparatus of the type described, comprising a pair of headers, a plurality of tubes interconnecting said headers, means for supplying condensable vapor to the tubes, and means for dividing the flow of condensate in a part of the condenser into a plurality of vertically-spaced paths through the tubes, and in another part of the condenser into a larger number of vertically spaced paths through the tubes.

4. Apparatus of the type described, comprising a pair of headers provided with separators for multi-pass operation, a plurality of tubes interconnecting said headers, means for supplying condensable vapor to the tubes, and means associated with at least one pass for controlling the number of tubes in that pass through which the condensate from preceding passes shall flow.

5. Apparatus of the type described; comprising a pair of headers provided with separators for multi-pass operation, a plurality of tubes interconnecting said headers, means for supplying condensable vapor to the tubes, and means associated with at least one pass for dividing the flow of condensate from preceding passes among a plurality of vertically-spaced tubes in said pass.

6. Apparatus of the type described, comprising a pair of headers, a plurality of tubes interconnecting said headers, means associated with said headers for providing multi-pass flow of fluid through said tubes, means for supplying condensable vapor to the tubes, and dam means for flooding a predetermined number of tubes in any 30 pass with condensate from the preceding passes.

7. Apparatus of the type described, comprising a pair of headers, a plurality of tubes interconnecting said headers, means associated with said headers for providing multi-pass flow of 40 fluid through said tubes, means for supplying condensable vapor to the tubes, and dam means associated with at least one pass for dividing the flow of condensate from preceding passes among a plurality of tubes at different vertical levels in 45 said pass.

8. In apparatus of the type described, a header comprising a cover plate, a tube sheet having a plurality of vertically spaced tubes secured thereto, means for supplying condensable vapor to said 50 tubes, fluid tight separators for providing multi-pass flow of fluid through said tubes, and a dam plate detachably interposed between said tube sheet and cover plate for causing condensate to flow through some of said tubes and for directing uncondensed vapor into other tubes at a lower level.

9. In apparatus of the type described, a header comprising a cover plate, a tube sheet having a plurality of vertically spaced tubes secured thereto, means for supplying condensable vapor to said tubes, fluid-tight separators for providing multi-pass flow of fluid through said tubes, and a dam plate detachably interposed between said tube sheet and cover plate, said dam plate comprising 60 a metallic sheet having an aperture associated with each pass, at least one of said apertures being so positioned above certain of said tubes that its lower edge may serve as a dam to the flow of condensate whereby the condensate is caused to 65 flow through a number of said tubes, and uncondensed vapor through other tubes at a lower level.

10. In apparatus of the type described, a header comprising a tube sheet having a plurality of vertically spaced tubes secured thereto, means 75

for supplying condensable vapor to said tubes, fluid tight separators for providing multi-pass flow of fluid through said tubes, and a cover plate provided with dam means integral with said cover plate and arranged to cause the flow of condensate through certain of said tubes and the flow of uncondensed vapor through other tubes at a lower level.

11. Apparatus of the type described, comprising a pair of headers provided with separators for multi-pass operation, a plurality of tubes interconnecting said headers, means for supplying condensable vapor to the tubes, and means associated with at least one pass for dividing the flow of condensate from preceding passes into a plurality of isolated paths at different vertical levels in said pass.

12. Apparatus of the type described, comprising a pair of headers provided with separators for multi-pass operation, a plurality of tubes interconnecting said headers, means for supplying condensable vapor to the tubes, and means comprising an auxiliary return bonnet for effecting the flow of condensate from one pass through a plurality of vertically-spaced tubes in the succeeding pass.

13. Apparatus of the type described, comprising a pair of headers provided with separators for multi-pass operation, a plurality of tubes interconnecting said headers, means for supplying condensable vapor to the tubes, and means comprising an auxiliary return bonnet to isolate the condensate flowing from a part of the tubes of

one pass, and direct it through tubes of the succeeding pass separate from the rest of the condensate.

14. Apparatus of the type described, comprising a pair of headers provided with separators for multi-pass operation, a plurality of tubes interconnecting said headers, means for supplying condensable vapor to the tubes, and at least one auxiliary return bonnet for directing the flow of the condensate from the lower tubes of one pass 10 into the upper tubes of the succeeding pass, said auxiliary return bonnet comprising a pair of separators and an inner cover plate.

15. Apparatus of the type described, comprising a pair of headers provided with separators for multi-pass operation, a plurality of tubes interconnecting said headers, means for supplying condensable vapor to said tubes, dam means for flooding a part of the tubes of at least one pass 15 with condensate from preceding passes, and drainage means accessible from the exterior of the condenser for draining such condensate from the flooded parts.

16. Apparatus of the type described, comprising a pair of headers, a plurality of tubes interconnecting said headers, dam means associated with said headers, and drainage means comprising a plug, one end of which is accessible on the exterior of the condenser and the other end of which removably engages a drain port through 20 and at the base of said dam means.

JULIUS BENZINGER.
